REGISTER CONTROL SYSTEM

Henry F. McKenney, Flushing, and George A. Lieske, Brooklyn, N. Y., assignors to The Sperry Corporation, a corporation of Delaware

Application November 18, 1949, Serial No. 128,216

3 Claims. (Cl. 271—2.6)

1

This invention relates to registry control systems and more particularly to a system for controlling the registration of the printing cylinders of a multicolor printing press.

An object of the invention is to provide a photoelectric registry control system which responds only to predetermined register marks on the running web. Another object is to provide a system of the above type with means to prevent actuation of the control mechanism in response to marks or printing on the web outside of a predetermined area containing the register mark.

Various other objects and advantages will be apparent as the nature of the invention is more fully disclosed.

In one embodiment of the invention the position of the printing cylinder is determined by scanning photoelectrically a member rotating with the cylinder and having a slit or other designation at its periphery and comparing the timing of the cylinder signal with a web signal obtained by scanning the register marks on the web. In order to prevent spurious actuation of the correction motor the slit or designation on the cylinder chamber is made sufficiently wide to produce a signal which persists over a period corresponding to the maximum error to be corrected and electrical gate means is provided to render the control effective only during such periods.

More specifically the cylinder member may comprise a disc rotating with the cylinder and having a slot of substantial angular extent through which a beam of light is passed from one or more light sources onto a pair of photoelectric tubes arranged to receive the beam in sequence as the disc rotates, with a slight overlap during which both tubes are energized. The signal obtained from the two tubes in sequence is converted into a wide flat topped wave which is used as a gate signal to condition the control tubes for actuation. One of the photoelectric tubes also produces a signal which constitutes the cylinder signal. A third photoelectric tube scans the web and produces the web signal. The relative timing of the cylinder and web signals and the coincidence of the gate signal are utilized to actuate the correction motor. In this way the correction motor does not respond to a false web signal derived from printing or the like at times when no gate signal is produced.

The novel features of this invention will be better understood from the following description, taken in connection with the accompanying drawings in which a specific embodiment has been set forth for purposes of illustration.

2

In the drawings:

Fig. 1 is a schematic diagram of a registry control circuit embodying the present invention; and

5 Fig. 2 is a detail view of the cylinder disc. Referring to the drawing more in detail, a printed web 10 is shown as fed by feed rolls 18 to a printing cylinder 11 which is driven by suitable means such as a drive shaft 16 connected through a gear box containing a differential and a register control motor 17 as set forth in detail in application Serial No. 100,890, filed June 23, 1949, for Intaglio Printing Press. The web 10 carries an index mark 12 which may comprise a mark printed by a previous printing cylinder of the press. A disc 13 having a peripheral slot 14 is shown for convenience as mounted on the shaft 15 of the cylinder 11. The disc may, however, be geared to the cylinder or a drum driven with the cylinder may be used.

Light rays from a source 20 are directed by lenses 21 and 22 in two separate beams 23 and 24 through the slot 14 onto photoelectric tubes 25 and 26, respectively.

25 The photoelectric tube 25 is provided with an anode 30 connected to an anode supply line 31 and with a cathode 32 connected through a resistor 33 to a D. C. source 34. The cathode 32 is connected to a grid 35 of a cathode follower tube 36 having an anode 37 connected to the line 31 and having a cathode 38 connected to ground through a resistor 39. The cathode 38 is connected through a blocking condenser 40 to the grid 41 of an amplifier tube 42 having a cathode 43 connected to ground through a resistor 44. The grid 41 is grounded through a resistor 45.

30 The photoelectric tube 26 is provided with an anode 50 connected to the line 31 and with a cathode 51 connected through a resistor 52 to a D. C. source 53. The cathode 51 is connected to the grid 54 of a cathode follower tube 55 having an anode 56 connected to the line 31 and a cathode 57 grounded through a resistor 58.

35 The cathode 57 is connected by a line 60 through a blocking condenser 61 to the grid 62 of an amplifier tube 63 having a cathode 64 grounded through a resistor 65. The grid 62 is grounded through a resistor 66.

40 The anodes 70 and 71 of the tubes 42 and 63 are connected together through a resistor 83 to the line 31 and through a condenser 84 to the grid 72 of an inverter tube 73 having an anode 74 connected through a resistor 75 to the line 31 and by a line 76 to the grid 77 of a cathode follower tube 78 having an anode 79 connected to a suitable D. C. source 80 and a cathode 81.

grounded through a resistor 82. The cathode 81 is connected by a lead 85 to control grids 86 and 87 of pentodes 88 and 89, respectively.

The lead 60 from the cathode of the tube 55 is also connected through a condenser 95 to the grid 96 of a tube 97 having an anode 98 connected through a resistor 99 to a D. C. lead 100, and by a lead 101 to a second grid 102 of the pentode 88. A tube 103 has an anode 104 connected through a resistor 105 to the lead 100 and by a lead 106 to a second grid 107 of the pentode 89. The tubes 97 and 103 are connected as an Eccles Jordan circuit in which the tubes are alternately made conducting and nonconducting in accordance with the signal applied to the grid 96. For this purpose the cathodes of the tubes 97 and 103 are connected together and grounded through a resistor 108, their plates and grids are cross-connected through resistors 110 and 111, and their grids are grounded through resistors 112 and 113, respectively.

The web signal is derived by a beam of light from a source 120 which is reflected from the web 18 onto a photo-electric tube 121. The light beam is focused on the area traversed by the register mark 12 by lens 122 and the reflected light is focused on the tube 121 by a lens 123. The photoelectric tube 121 has an anode connected to a D. C. supply line 124 and a cathode 127 connected through a resistor 125 to a D. C. source 126. The cathode 127 is connected to grid 129 of a cathode follower tube 129 having an anode connected to the line 124 and a cathode grounded through a resistor 119 having a variable tap 130. The tap 130 is connected by a lead 131 to third grids 132 and 133 of pentodes 88 and 89, respectively. Cathodes 135 and 136 of pentodes 88 and 89 are connected to the D. C. line 109.

Anodes 138 and 139 of the pentodes 88 and 89 are connected by leads 140 and 141 to a pulse converter 142 having output leads 143 and 144 connected to control the operation of the register motor 17. The pulse converter 142 is arranged to apply a D. C. control voltage to the lines 143 and 144 the polarity and value of which is dependent upon the amount and direction of unbalance between the space currents through the respective pentodes 88 and 89.

In the operation of this system the photoelectric tubes 26 and 25 are pulsed in sequence by light beams 24 and 23 as the slot 14 in the disc 13 is brought into registration with the light beams during the rotation of the disc. The slot 14 is so designed that the tube 25 is pulsed just before the tube 26 is deenergized so that the combined pulses are continuous for the duration of the gating period. The pulse on the tube 26, through the cathode follower tube 55 produces a positive pulse on the lead 60 and on the grids 62 and 96 of tubes 63 and 97, respectively, which renders these tubes conductive for the duration of the pulse. In a similar manner the tube 42 is made conductive for the duration of the light pulse on the photoelectric tube 25. Due to the anode resistor 83 a negative pulse is produced on the anodes 70 and 71 and applied to the grid 72 of the tube 73 for the duration of the two light pulses. This negative pulse may have a sharp peak at the instant of overlap of the two light pulses but this peak is eliminated by the tube 73 which is adjusted to be blocked during the entire period of the negative pulse on its grid. Through the tube 78 the negative pulse on the grid 72 is converted to a positive pulse on the grids 86 and 87 which extends over the combined period of the pulses on the photoelectric tubes 26 and 25 and

permits the pentodes 88 and 89 to operate when the proper signals are applied to their other grids. When no positive gate signal is applied to the grids 86 and 87 the grids are maintained sufficiently negative to block the pentodes and thus prevent operation thereof except during the gate period.

The tube 97 is normally nonconducting and the tube 103 conducting when no signal is received from the photoelectric tube 26. With the tube 97 nonconducting a positive voltage is applied to the grid 102 of the pentode 88 from the self biased anode 98 of the tube 97. With the tube 103 conducting a negative voltage is applied to the grid 107 of the pentode 89. Pulsing of the photoelectric tube 26 applies a positive pulse to the grid 96 which renders the tube 97 conducting and the tube 103 nonconducting, thereby placing a negative pulse on the grid 102 and a positive pulse on the grid 107 for the duration of the pulse on the photoelectric tube 26. Thus the pentode 89 is conditioned for conducting during the period of the light pulse on the tube 26 and the pentode 88 is conditioned to conduct at other times during the gating period, but neither pentode can conduct outside of the gating period due to the cut-off by the grids 86 and 87.

The web signal, through the photoelectric tube 121 and tube 129, produces a positive pulse on the grids 132 and 133 of the pentodes 88 and 89. This will render conducting the pentode which is conditioned at that instant by positive voltages on both of its other grids. If the web signal coincides with the pulsing of the photoelectric cell 26 the pentode 89 is rendered conductive and if it occurs during the gating period but outside of the period of pulsing of the tube 26, that is during the pulsing of the tube 25, the pentode 88 becomes conductive. The operation of the respective pentodes thus indicates a lead or a lag in web position and a correcting signal is sent over the lines 143 and 144 to the registry control motor 17.

As stated above the tube 25 is preferably pulsed just before the tube 26 is deenergized, and Fig. 2 represents the relative position of the disc 13 at this instant of overlap. It will be understood, however, that the overlap is merely a safety factor so as to assure an absence of gap in the gating period. In correct registry the web signal period is equally divided by the cut-off of the pulsing of tube 26 and the control is responsive to the differential of the web signal on the two sides of that cut-off.

If the web signal occurs at any time outside of the gating period the pentodes remain blocked and no response is produced in the motor 17. Hence any mark or designation on the web between the positions reserved for the registry mark will not produce an undesired operation of the correction motor and the entire area of the web, except for a limited area around each registry mark, can be used for the usual printing.

The system has been described for convenience as applied to a multicolor printing press. It may however be applied to other uses, such as to the registry control of cutting knives or perforating knives in a web cutting or perforating machine. Various embodiments will be apparent to a person skilled in the art.

What is claimed is:

1. In a control system for a machine having an element operating upon a moving web of material in predetermined relationship with respect to register markings thereon, means for driving said web and said element at predetermined speeds, a registry control mechanism including a correc-

tion motor connected to adjust the relative driven positions of said web and said element, photoelectric scanning means scanning said web and having means producing a web pulse corresponding to the passage of each of said register markings, a pair of other photoelectric scanning means, a member driven with said element and having a gating area arranged to pulse said other photoelectric scanning means in continuous sequence and in predetermined relationship with the position of said element, a circuit connected to produce a gating signal in response to and of a duration corresponding to the sequence of pulses on said other scanning means, a circuit connected to produce a pulse in response to the individual pulse of one of said other scanning means, and a control circuit having means responsive to the coincidence of said web pulse, said gating pulse and said individual pulse to operate said correction motor in one direction, and having means responsive to the coincidence of said web pulse, said gate pulse, and the absence of said individual pulse to operate said correction motor in the other direction.

2. In a control system for a machine having an element operating upon a moving web of material in predetermined relationship with respect to register markings thereon, means for driving said web and said element at predetermined speeds, a registry control mechanism including a correction motor connected to adjust the relative driven positions of said web and said element, photoelectric scanning means scanning said web and having means producing a web pulse corresponding to the passage of each of said register markings, a pair of other photoelectric scanning means, a member driven with said element and having a gating area arranged to pulse said other photoelectric scanning means in continuous sequence and in predetermined relationship with the position of said element, a control circuit to actuate said correction motor including a pair of pentodes, connections applying a positive pulse to one control grid of each pentode in response to said web pulse, connections applying a positive pulse to a second grid of one pentode and a negative pulse to a second control grid of the other pentode in response to a pulse on one of said pair of other scanning means and reversing the pulses on said second control grid on cessation of said last pulse, and connections applying a positive pulse to third control grids of both of said pentodes in response to a pulse on either of said other scanning means, whereby one or the other of said pentodes becomes conductive in response to coincidence of the web pulse with one or the other of the pulses of said other scanning means and both pentodes remain nonconductive in the absence of a pulse on one or the other of said other

scanning means, and a circuit responsive to the selective actuation of said pentodes to actuate said correction motor in a direction to maintain a predetermined relationship between said web pulse and said other pulses.

3. In a control system for a machine having an element operating upon a moving web of material in predetermined relationship with respect to register markings thereon, means for driving said web and said element at predetermined speeds, a registry control mechanism including a correction motor connected to adjust the relative driven positions of said web and said element, photoelectric scanning means scanning said web and having means producing a web pulse corresponding to the passage of each of said register markings, a pair of other photoelectric scanning means, a member driven with said element and having a gating area arranged to pulse said other photoelectric scanning means in continuous sequence and in predetermined relationship with the position of said element, circuit means including two pentode electronic tubes and adapted when the tubes are conductive to reversibly energize the correction motor, means normally positively biasing one grid of one tube and negatively biasing the corresponding grid of the other tube, means responsive to the pulsing of one of the said pair of other scanning means for reversing the bias on said grids, means normally negatively biasing a second grid in each tube, means responsive to the gate pulsing of said pair of other scanning means for reversing the bias on said second grids, means normally negatively biasing the third grid of each tube, and means responsive to a web pulse for reversing the bias on said third grids, whereby the coincidence of the web pulse with the pulsing of one of said pair of other scanning means renders one pentode conductive and the coincidence of the web pulse with the pulsing of the other of said pair of scanning means renders the other pentode conductive and the control of the correction motor is responsive to the difference in the time that the period of the web pulse is coincident with the respective periods of pulsing of the scanning means of the said pair.
